UNITED STATES PATENT OFFICE.

AXEL B. KASPARSON, OF WORCESTER, MASSACHUSETTS, ASSIGNOR TO HOWARD BROTHERS MANUFACTURING COMPANY, OF WORCESTER, MASSACHUSETTS, A CORPORATION OF MASSACHUSETTS.

DEVICE FOR ATTACHMENT TO CARD-CLOTHING.

No. 896,023.

Specification of Letters Patent.

Patented Aug. 11, 1908.

Application filed July 16, 1907. Serial No. 384,051.

To all whom it may concern:

Be it known that I, AXEL B. KASPARSON, of Worcester, in the county of Worcester and State of Massachusetts, have invented a new 5 and useful Device for Attachment to Card-Clothing, of which the following is a specification.

My invention relates to card clothing and especially to stiffening and protecting the 10 ends of the clothing when in place on the flats.

My object is to provide an end stiffener or protector which can not only be readily put in place but which will be certain to remain in place without deleterious effect on the 15 clothing; and my invention is a device, preferably of metal, which covers the end of the clothing and has means to positively engage that end.

A feature of my invention consists in making 20 my device with a channel which covers the end of the clothing and in which the end is clamped.

In the drawings Figure 1 is an end view of a flat with the card clothing and my device in 25 place; Fig. 2 is a side view of the same but partly in section; Fig. 3 is a plan of the clothing with my device in place; Fig. 4 is a perspective of my device; Fig. 5 is another view of my device; and Fig. 6 is an enlarged sec- 30 tional view.

Card clothing A comprising the usual cloth foundation a, and teeth a' is attached to flat B by side fasteners C C. These fasteners cover the side edges of the card clothing but 35 leave the ends to be otherwise stiffened and protected. It is extremely important to have end coverings to prevent the unraveling of the ends of the clothing for two reasons, namely, to prevent the unraveling from 40 weakening the clothing itself and so loosening and weakening the foundation for the teeth, and also to prevent the unraveled ends of the clothing from interfering with the operation of the carding machine by getting caught in 45 other parts of the machine. It is also of great importance that the clothing be stiffened so that it will not tend to pull out from the side clips.

The end clips heretofore used have acted 50 with some efficiency as mere protectors but they have either been so imperfectly attached to the clothing as to be readily shaken off, or they have been so securely hooked to the body of the clothing that they work into

and gradually tear it open and seriously 55 weaken it.

My end clip D comprises lip d parallel with the wire teeth, portions d' and d² to engage respectively the upper and lower surfaces of the clothing, portion d³ covering the end of 60 the clothing and fingers d⁴ d⁴ to aid in holding the clip in position. Portion d' has burs or spikes d⁵ d⁵ to firmly engage the clothing while portion d² has burs d⁶ d⁶ for the same purpose. These burs are at a distance edge- 65 wise from portion d³ and they act with portion d³ to clamp the edge of the clothing which is held as in a vise, and which therefore cannot unravel. I prefer to have the upper and lower burs in staggered relation as 70 shown, as in such case I get a more efficient clamping function. While these burs most securely hold the device in place they have no tendency to tear or weaken the clothing at any part which forms the foundation or 75 base for the wire teeth.

I prefer to have the portions d' and d² which form a channel for the clothing pinched together or clenched as indicated in Fig. 6, as this gives an additional clamping 80 function supplementing the clamping function above described, and aiding the action of the spikes d⁵ d⁵ and d⁶ d⁶.

Among the advantages of my device it may be noted that it is held firmly in place 85 without acting in any way harmfully upon the clothing and at the same time it prevents unraveling and therefore removes all danger of unraveled ends interfering with the operation of the machine. Furthermore, it is a 90 very important advantage to have the device positively engage the end of the clothing as this enhances the stiffening function in addition to insuring a positive engagement at the desired part of the clothing. 95

What I claim is:

1. As a new article of manufacture a device for attachment to card clothing comprising two parallel walls to engage the top and bottom surfaces of the end edge of the 100 clothing and a perpendicular wall to extend along the end edge of the clothing, the whole forming a channel which is slipped on to the edge of the clothing; and inwardly projecting spikes on one of said parallel walls forced into 105 the clothing after the channel has been slipped upon the edge of the clothing.

2. As a new article of manufacture a de-

vice for attachment to card clothing comprising two parallel walls to engage the top and bottom surfaces of the end edge of the clothing and a perpendicular wall to extend 5 along the end edge of the clothing, the whole forming a channel which is slipped on to the edge of the clothing; and inwardly projecting spikes on one of said parallel walls forced into the clothing after the channel has been

slipped upon the edge of the clothing, the 10 two parallel walls being clenched together so as to grip the clothing directly between them while the spikes positively engage the clothing.

AXEL B. KASPARSON.
